WIRE ROPE MANUFACTURING MACHINE

William T. MacCreadie, Lewisburg, Pa., assignor, by mesne assignments, to Sunbury Wire Rope Manufacturing Company, Sunbury, Pa., a corporation of Pennsylvania

Application May 13, 1947, Serial No. 747,803

8 Claims. (Cl. 57—68)

1

This invention is a wire rope manufacturing machine, and pertains particularly to that type of machine capable of producing a rope or cable in which a plurality of wires are wrapped or twisted together to provide an elongated strand.

An object of the invention is to provide a machine for the production of what might be called small cables, composed of relatively few strands, and wherein the finished cable may be produced at high speed and by the use of simplified machinery.

A further object of the invention is to provide a wire rope manufacturing machine of the character generally stated which has its mechanism so assembled and operatively connected as to occupy a minimum of space, and further characterized by an assemblage which minimizes the opportunity for vibration.

A further object of the invention is to provide a wire rope machine involving automatic mechanism featured by power means for synchronizing the operations of the guider and wind-up bobbin which means is not effected by centrifugal force, resulting in an insurance of even wind of the finished cable upon the wind-up bobbin.

With the foregoing objects in view, together with others which will present themselves as the description proceeds, the invention consists in the novel construction, combination and arrangement of parts, all as will be described more fully hereinafter, illustrated in the drawings, and specifically set forth in the claims.

In the drawings:

Fig. 1 is a top plan view of a wire rope manufacturing machine embodying the invention.

Fig. 2 is a side elevation of the improved machine.

Fig. 3 is a transverse sectional view taken substantially upon line 3—3 of Fig. 2, and

Fig. 4 is a detail fragmentary sectional view taken through one end of the wind-up bobbin cradle and illustrating the assemblage of the parts thereof.

Referring now more particularly to the drawing, the wind-up bobbin unit includes an elongated cradle represented generally at 5, including the end members 6—7 connected by side members 8 and 9. Arranged longitudinally within the cradle and in spaced parallel relation to each other are sills 10—11, which rotatably support between them a transversely disposed wind-up bobbin supporting shaft 12, a cam drum shaft 13 and a haul-off drum shaft 14. These shafts are disposed transversely of the cradle in spaced parallel relationship with one another and are

2

preferably disposed in the longitudinal axis of the cradle. The shaft 12 carries a wind-up bobbin of conventional form indicated at 15, while the cam drum shaft 13 carries a cam drum 16 having therein a spiral groove 17, in which groove engages one end of a guide member 18 mounted for sliding movement upon the guide bar 19 also secured between the sills 10—11. The shaft 14 has secured thereto a haul-off drum 20.

10 The ends of the cradle 5 are provided with outwardly extending longitudinally aligned hollow trunnions 21 and 22. These trunnions are rotatably supported in the bearing members 23. The trunnion 22 projects through its adjacent supporting bearing 23 and has associated therewith a twister die 24 of conventional form, in which the strands 25 of wire are twisted together in forming the wire rope, indicated in its completed form at 26. The strands 25 are led from 20 feeder bobbins 27 mounted in cradles 28 rotatably arranged beyond the feed end of the cradle 5. These feeder bobbins and the cradle supporting the same may take any desired form and may be used in any desired number, the number, 25 of course, depending upon the number of strands to be included in the completed cable. The feeder bobbin cradles are rotated in their bearings 29 by power derived from the main source of power including a shaft 30. This shaft has secured at 30 one end thereof a pulley 31 over which passes a belt 32 also passing around a drum 33 on a supporting shaft of one of the feeder bobbin cradles. Belts 34 connect the shafts of the feeder bobbin cradles in such manner that the cradles will be 35 caused to rotate in synchronism and at a speed determined by the speed of rotation of the shaft 30.

The outer end of the trunnion 21 of the wind-up bobbin cradle has affixed thereto a pulley or drum 35, over which passes a belt 36 which also passes around a pulley or drum 37, affixed to shaft 30. By this construction it is obvious that the cradle 5 and the mechanism carried thereby is caused to rotate when the main power source or shaft 30 is rotated.

40 Rotatably mounted within the trunnion 21 is a stub shaft 38. The trunnion 21 constitutes a bearing for one end of this shaft 38 while the fixed bearing member 39 rotatably supports the 45 opposite end of the said stub shaft. This shaft has keyed or otherwise affixed thereto a pulley 40, over which passes a belt 41 also passed around a drum or pulley 42 affixed to the main source of power 30.

The stub shaft 38 projects at one end into

the cradle 5 and has keyed thereto a gear 43 in mesh with a smaller gear 44 affixed to a shaft 45 disposed longitudinally of the cradle and supported in bearings 46 in the sill 11. The opposite end of this shaft 45 has a bevel gear 47 affixed thereto which meshes with a similar gear 48 affixed to one end of the haul-off drum shaft 14. From this construction it is apparent that rotary movement applied to the stub shaft 38 by belt 41 will be transmitted through main gear 43 to gear 44 and shaft 45, and through the instrumentality of bevel gears 47-48 will be transmitted to the haul-off drum shaft 14.

The inner end of the stub shaft 38 loosely or rotatably supports a gear 49 in mesh with a smaller gear 50 keyed or otherwise affixed to a shaft 51 mounted in suitable bearings 52 upon sill 10 of the cradle. The shaft 51 has affixed thereto a bevel gear 53, in mesh with a similar gear 54 affixed to the adjacent end of wind-up bobbin shaft 12. Also mounted upon sill 10 and longitudinally of the cradle 5 is a second shaft 55, to one end of which is connected a bevel gear 56 in mesh with similar gear 54. The shaft 55 is supported in bearings 57 carried by the sill 10. The shaft 55 is provided with a worm 58 which engages a worm gear 59 secured to cam drum shaft 13.

The gear 49 has affixed thereto on its inner face and concentric with the gear a brake band 60 which encircles and grips a brake drum 61 keyed or otherwise affixed to the adjacent end of stub shaft 38.

When the stub shaft 38 is rotated, frictional engagement between the drum 61 and band 60 will cause gear 49 to rotate, which in turn rotates spur gear 50, shaft 51 and bevel gear 53. This rotary motion is transmitted to the wind-up bobbin through gear 54, while gear 56 operates shaft 57 to rotate the cam drum shaft through the instrumentality of the worm and worm gear arrangement 58-59. It is obvious, therefore, that the shafts 12 and 13 are driven from the same power source and will operate simultaneously at the speeds determined by the ratio of gears and worms. Any slippage in the power connection including the drum 61 and band 60 will simultaneously affect the wind-up bobbin and the feed guider.

In operation, the strands from the feeder bobbin, in the number desired, are led through the twister die 24 and through the hollow trunnion 22 and in their twisted form around the haul-off drum 20 to guide pulley or sheave 62, from whence the completely twisted and properly formed wire passes through the guide member 18 and then around the wind-up bobbin 15. Upon power being applied to the main power shaft 30, the cradle 5 rotates upon its trunnions, the haul-off drum 20 rotates to draw the completed cable through the twister die, while at the same time the wind-up bobbin reels the completed cable upon itself, the cable being guided in proper laps by the guide member 18 travelling in cam groove 17. At the same time, the feeder bobbin cradles 28 are being rotated upon their axes while the wire strands thereof are being paid off from the bobbins 27 carried by the said cradles. It will be understood that the pulley and belt drive connections for the feeder bobbins will be properly synchronized with the belts imparting power to the wind-up bobbin cradle 5 and the several parts operatively associated therewith.

A machine so constructed occupies a relatively small space and at the same time is capable of

rapid operation to produce a relatively great amount of unbroken twisted strand in a given time. By locating the power shafts for driving the haul-off drum and for powering the wind-up bobbin and the cam drum from opposite sides of the cradle, the latter is properly balanced so that vibrations due to high rotative speed of the cradle are reduced to a minimum. The substitution of a cam drum for feeder operating devices heretofore employed insures a more even feed of the completed wire to the wind-up bobbin. By synchronizing the movements of the cam drum and the wind-up bobbin, an even and regular lap in the winding operation is assured. Any slippage that might occur is translated to both the wind-up bobbin and the cam drum. This arrangement assures an even wind of the completed cable or rope upon the bobbin whether the bobbin be nearly empty or nearly full.

Due to the fact that the friction brake is disposed concentrically with the stub shaft 38, centrifugal influences upon this power connection are eliminated.

Having thus fully described my invention, I claim:

1. In a wire rope manufacturing machine, an elongated cradle rotatably mounted upon its longitudinal axis, a wind-up bobbin a cam drum and a haul-off drum rotatably supported in said cradle upon axes disposed transversely of said cradle and in spaced relation to one another, means for rotating said cradle, power means supported by and located on one side of said cradle for rotating said bobbin and said cam drum, and power means supported by and located upon the opposite side of said cradle for rotating said haul-off drum.

2. In a wire rope manufacturing machine, an elongated cradle rotatably mounted upon its longitudinal axis, a wind-up bobbin a cam drum and a haul-off drum rotatably supported in said cradle upon axes disposed transversely of the cradle and in spaced relation to one another, means for rotating said cradle, a power shaft rotatably mounted on one side of said cradle and disposed longitudinally thereof, a drive connection between said shaft and said bobbin, a drive connection between said bobbin and said cam drum, a brake to govern the speed of said power shaft, a second power shaft rotatably mounted upon the opposite side of said cradle and disposed longitudinally thereof, and a power connection between said second power shaft and said haul-off drum.

3. In a wire rope manufacturing machine, a cradle mounted for rotation of its longitudinal axis, a wind-up bobbin shaft and a cam drum shaft rotatably supported in said cradle with their axes disposed transversely of said cradle, a cam drum on said cam drum shaft, a shaft rotatably supported on one side of said cradle, intermeshed bevel gears on said shaft and said bobbin shaft, a second shaft on said cradle, a bevel gear on one end of said shaft in mesh with the bevel gear of said bobbin shaft, a worm drive connection between the other end of said second shaft and said cam drum shaft, a guide mounted in said cradle for sliding movement laterally thereof and in engagement with the cam of said drum, and means for driving said first named shaft.

4. In a wire rope manufacturing machine, a cradle mounted for rotation upon its longitudinal axis, a wind-up bobbin shaft a cam drum shaft and a haul-off drum shaft all rotatably

supported in said cradle with their axes disposed transversely thereof, a cam drum on said cam drum shaft, a shaft rotatably supported on one side of said cradle, intermeshed bevel gears on said shaft and said bobbin shaft, a second shaft on said cradle, a bevel gear on one end of said shaft in mesh with the bevel gear of said bobbin shaft, a worm drive connection between the other end of said second shaft and said cam drum shaft, a guide mounted in said cradle for sliding movement laterally thereof and in engagement with the cam of said drum, means for driving said first named shaft, an elongated shaft rotatably mounted upon the opposite side of said cradle and disposed longitudinally thereof, a drive connection between said elongated shaft and said haul-off drum shaft, and means for rotating said elongated shaft.

5. In a wire rope manufacturing machine, a bobbin cradle, a hollow trunnion connected to one end of said cradle and rotatably supporting the latter, a bobbin and a cam drum rotatably supported in said cradle, a power shaft extending through said trunnion, a second shaft rotatably supported in said cradle, a power connection between said second shaft and said bobbin and cam drum, a main gear rotatably mounted on said power shaft, a gear affixed to said second shaft and in mesh with said main gear, a brake drum affixed to said main shaft, a brake band affixed to said main gear and engaged with said drum, means for rotating said trunnion, and means for rotating said main power shaft.

6. In a wire rope manufacturing machine, a bobbin cradle, a hollow trunnion connected to one end of said cradle and rotatably supporting the latter, a bobbin a cam drum and a haul-off drum all rotatably supported in said cradle, a power shaft extending through said trunnion, a second shaft rotatably supported in said cradle, a power connection between said second shaft and said bobbin and cam drum, an elongated shaft supported by said cradle and in spaced parallel relation to said second shaft, a main gear rotatably mounted on said power shaft, a gear affixed to said second shaft and in mesh with said main gear, a brake drum affixed to said main shaft,

a brake band affixed to said main gear and engaged with said drum, a second gear affixed to said main power shaft, a drive connection between said second gear and said elongated shaft, means for driving said haul-off drum from said elongated shaft, means for rotating said trunnion, and means for rotating said main power shaft.

7. In a wire rope manufacturing machine, a rotatably mounted cradle, a wind-up bobbin a cam drum and a haul-off drum all mounted for rotation in said cradle, a single power source for rotating said wind-up bobbin and said cam drum, positive drive means for rotating said haul-off drum, and a slip drive connection between said positive drive means and said single power source.

8. In a wire rope manufacturing machine, a rotatably mounted cradle, a wind-up bobbin a cam drum and a haul-off drum all mounted for rotation in said cradle, a power shaft, a positive drive connection between said power shaft and said haul-off drum, a counter shaft to drive said wind-up bobbin and said cam drum simultaneously and at predetermined uniform speeds, a guide member operatively connected with said cam drum, a gear loosely mounted on said power shaft, a gear affixed to said counter shaft in mesh with said first named gear, a brake drum on said power shaft, and a brake band on said loose gear engaged with said drum.
